Specification of Letters Patent.

Patented Oct. 7, 1919.

Application filed August 16, 1917. Serial No. 186,607.

To all whom it may concern:

Be it known that I, WILLIAM L. SCHELLENBACH, a citizen of the United States, residing at Cincinnati, county of Hamilton, and State of Ohio, have invented an Improvement in Milling-Machines, of which the following description, in connection with the accompanying drawings, is a specification, like characters on the drawings representing like parts.

10 The invention hereinafter described relates to milling machines and other machine tools.

Machines of this type usually comprise a 15 standard supporting a knee, saddle and table. The knee may be fed vertically along the standard, and the saddle and table may be fed transversely to one another on the knee.

20 One of the objects of the invention is to provide improved speed change mechanism mounted in the knee for feeding the knee, saddle or table, or any of them, at different speeds appropriate for operation of the tool 25 on the work.

Another object of the invention is to provide means including a rotor on the standard for imparting a rapid traverse to the knee, saddle and table, or any of them, to 30 carry the work quickly to different positions according to conditions as desired.

Another object of the invention is to provide simple and effective mechanism for transmitting the drive to the feeding mechanism in the knee from work feed and rapid traverse rotors on the standard, without requiring the usual flexible, extensible shaft between the standard and knee.

40 Another object of the invention is to provide simple and effective means including a control carried by the knee whereby the work feed and rapid traverse rotors on the standard may alternatively be rendered effective to feed the work support, and the direction of feed thereof may be determined.

Still another object of the invention is to provide improved mechanism for controlling the starting and stopping of the various feeds and the rapid traverse.

50 With the aforesaid and other objects in view, the character of the invention may be best understood by reference to the fol-

lowing description of one good form thereof shown in the accompanying drawings, wherein:—

55 Figure 1 is a view partly in side elevation and partly in vertical section of a milling machine embodying the invention;

Fig. 2 on an enlarged scale is a horizontal section taken on line 2—2 of Fig. 1;

60 Fig. 3 is a vertical section taken on line 3—3 of Fig. 2;

Fig. 4 on an enlarged scale is a view partly in side elevation and partly in vertical section showing the mechanism for 65 feeding the knee, saddle and table;

Fig. 5 on an enlarged scale is a vertical section taken on line 5—5 of Fig. 4;

Fig. 6 is a horizontal section taken on line 6—6 of Fig. 5;

70 Fig. 7 is a view partly in front elevation and partly in vertical section on a plane at right angles to the vertical section shown in Fig. 4;

Fig. 8 is a sectional detail of devices 75 forming a part of the means for starting and stopping the feeds;

Fig. 9 on an enlarged scale is a vertical section taken on line 9—9 of Fig. 12;

Fig. 10 on an enlarged scale is a vertical 80 section taken on line 10—10 of Fig. 12;

Fig. 11 is a horizontal section taken on line 11—11 of Fig. 7;

Fig. 12 is a horizontal section taken on line 12—12 of Fig. 7;

85 Fig. 13 on an enlarged scale is a vertical section showing the clutch for the work feed gear, the clutch for the rapid traverse pulley and the shaft for operating said clutches;

Fig. 14 is a horizontal sectional detail of 90 parts of the mechanism operated by movement of the table for arresting the feed thereof;

Fig. 14^a is a vertical section disclosing 95 parts shown in Fig. 14;

Fig. 15 on an enlarged scale is a sectional detail of parts of the mechanism operated by the knee and saddle for arresting the feed thereof; and

100 Fig. 16 on an enlarged scale is a vertical section through the guard for the handle for controlling the work feed, the rapid traverse and the direction of feed.

Referring to the drawings, the machine

shown therein as embodying the invention comprises a standard 1 (Fig. 1) having uprights 3 thereon provided with bearings in which is journaled the usual tool actuating spindle 5. An arm 7 may be secured in said uprights adjacent the upper ends thereof and project forwardly from said standard to provide an outboard bearing for said spindle. A work feed rotor, in the present 10 instance, in the form of cone pulley 9 may be mounted on said spindle and may be driven by a belt (not shown) in the usual manner. To support the work in proper relation to the tool on the spindle, a knee 11 15 may be provided having a dovetail groove adapted to receive and slide vertically along a dovetail projection 15 on the front face of said standard.

A saddle 17 may be mounted on and slide 20 along said knee toward and from said standard and is guided by a dovetail projection 19 on said knee entering a similarly shaped groove on said saddle.

A table 21 may be mounted on and slide 25 transversely of said knee and be guided by a dovetail projection 23 entering a similarly shaped groove on the saddle.

To elevate and lower the knee, it may be provided with the usual screw 25 (Fig. 4) 30 mounted in a bearing in a foot 27 on said standard beneath said knee. This screw has a bevel gear 29 fast thereon which may be rotated manually by the bevel pinion 31 fast on a shaft 33 (Fig. 12) journaled in bearings in the knee and provided with the usual hand-crank (not shown). To rotate the knee feed screw automatically, there may be provided a bevel pinion 35 (Fig. 4) meshing with the bevel gear 29 and mounted 35 fast on a shaft 37 journaled in bearings in the knee. This shaft has a pinion 39 fast thereon adapted to be driven at the times desired by means of a shiftable gear 41 splined to a shaft 43 (Fig. 11) having one 40 end journaled in a bearing in the knee and its opposite end journaled in a bearing 45 in the end of a shaft 47 journaled in bearings in the knee. The shafts 43 and 47 may be connected at the times desired by means of 45 a clutch 49 adapted to be controlled by means more fully hereinafter described. The shaft 47 has a sleeve 51 splined and slideable thereon and provided at one end thereof with a gear 53 meshing with a gear 55 on a shaft 57 journaled in bearings in the knee. The gear 55 is driven by one of a series of cone gears 59 on a shaft 61 journaled in bearings in a tumbler 63 mounted on and adapted to oscillate about the shaft 57. The 50 tumbler is keyed to a sleeve 65 projecting toward the front of the knee, where it receives a crank 67 having a handle 69 adapted to be held in different positions of adjustment by a spring-pressed pin 71 in

said handle adapted to enter any of a series 65 of holes in the face of the knee.

The tumbler gears may be driven either by a pinion 73 (Fig. 4) or a gear 75 fast on a shaft 77 having one end journaled in a sliding bearing 79 (Figs. 4 and 12) and its 70 opposite end slidably mounted in and splined to a sleeve shaft 81 journaled in a bearing in the knee. The slideable bearing 79 may be adjusted to bring either the pinion 73 or the gear 75 in position to mesh with 75 any of the cone gears 59 carried by the tumbler in order to impart different speeds thereto. To shift the bearing 79 it may have a rack 83 (Fig. 4) meshing with a worm 85 on a stud shaft 87 journaled in a 80 bearing in the knee and having at one end thereof a crank 89 provided with a handle 91 adapted to be held in different positions of adjustment by a spring-pressed pin 93 adapted to enter any of a series of holes on 85 the face of the knee.

To change the speeds, it is merely necessary to rock the tumbler gears by the handle 69 and shift the sliding gears by the handle 91 to the positions desired. In the present instance of the invention, the tumbler carries four different sized gears adapted to mesh with either the pinion 73 or the gear 75, thereby providing eight different speeds by the simple adjustments described. 95

It will be understood, however, that the number of tumbler gears may be varied to furnish a different number of speeds if required.

Simple means may be provided to double 100 the number of speeds obtained by the cone gears and the gears 73 and 75. To accomplish this, a pinion 95 (Fig. 11) may be mounted fast on the shaft 57, referred to, driven by the cone gears, and said pinion 105 may mesh with gear 97 loose on the shaft 47, referred to. To connect the gear 97 with the shaft 47 the sleeve 51 and the hub of the gear 97 may be provided with opposed teeth forming a clutch 99. This clutch may be shifted manually by means of a shoe 101 entering the circumferential groove in said sleeve, said shoe being fast on a shaft 103 (Fig. 1) projecting beyond one side of the knee and having a crank fast thereon provided with a handle 105 having a spring-pressed pin adapted to engage either of two holes 107 on a plate on said knee. 110

By the construction described the handle may be readily rocked to open the clutch to its position shown in Fig. 11, in which the drive from the gear 55 is to the shaft 47 through the gear 53; or the handle may be rocked to close the clutch, thereby sliding the sleeve 51 toward the left of Fig. 11, moving the gear 53 out of mesh with the gear 55 and connecting the gear 97 to the shaft 47. Then the drive from the cone gears will be 115 120 125

through the gear 55, its shaft 57, the pinion 95, through the gear 97 to the shaft 47.

Having described the mechanism whereby a number of different speeds of feed are provided for the knee, next will be described simple transmission means whereby these different speeds of feed may be imparted to the saddle. This may be accomplished through the shiftable gear 41, referred to, 5 which is adapted to be slid toward the left (Fig. 11) into mesh with a gear 109 fast on the saddle feed screw shaft 111 journaled in bearings in the knee. This feed screw shaft works in a nut 113 (Fig. 4) carried 10 by a bracket 115 depending from the saddle. The saddle screw shaft may project forwardly beyond the front face of the knee to receive the usual handle (not shown) permitting the saddle to be fed manually. 15

Next will be described simple means whereby the table may be fed along the saddle at any of the speeds obtained by any of the feeds for the knee and saddle. To accomplish this, the shiftable gear 41 is 20 adapted to slide toward the left (Fig. 4) into mesh with a gear 117 fast on a shaft 119 journaled in bearings in the knee. This shaft projects through and is splined to a sleeve 121 journaled in a bearing in the 25 saddle bracket 115, referred to, said sleeve having a bevel gear 123 fast thereon driving a bevel gear 125 fast on a sleeve shaft 127 projecting upwardly through and journaled in a vertical bearing in 30 said bracket. The upper end of this sleeve shaft has a gear 129 fast thereon meshing with a gear 131 having a hub 132 journaled in a bearing on the saddle and keyed to the table feed screw shaft 133 jour- 35 naled in bearings adjacent the opposite ends of the table. This screw shaft is threaded into a nut 135 (Fig. 7) secured to the saddle. 40

The saddle may be formed in two parts 137 and 139, one of which may swivel about 45 the saddle bracket and thereby enable the table to be positioned on a vertical axis at any angle desired. However, the feed transmission mechanism through the saddle bracket described enables the feed to be 50 transmitted to the table in any of its positions of rotative adjustment. Also, the transmission described is readily adaptable to a plain milling machine in which the saddle is not swiveled.

As stated, the shiftable gear 41 may slide 55 on its shaft to three different positions of adjustment,—one for feeding the knee, another for feeding the saddle, and another for feeding the table. To adjust said gear 60 along its shaft to these positions, its hub (Fig. 4) may have a circumferential groove therein receiving a yoke 141 fast on an axially sliding shaft 143 projecting to and through the front face of the knee, where it

receives an operating knob 145. When this 65 knob is thrust to its innermost position shown in full lines, the shiftable gear will mesh with the pinion 39 and transmit the feed to the knee. When the knob is pulled outward to its position 145^a indicated in 70 dotted lines, the shiftable gear will mesh with the gear 109 and transmit the feed to the saddle. When the knob is pulled to its outermost position 145^b indicated in dotted lines, the shiftable gear will mesh with the 75 gear 117 and transmit the feed to the table.

Next will be described the means for shifting the clutch 49, referred to, to control the starting and stopping of the feeds for the knee, saddle and table. To accomplish this, 80 a T-shaped lever 147 (Figs. 11 and 12) may be provided pivotally mounted within the knee and having an arm 149 with a shoe 149^a working in a circumferential groove in the clutch 49. This T-lever may be rocked 85 to open and close the clutch by a fork 151 (Figs. 7 and 8) engaging a rounded end 152 (Fig. 11) of said lever. The fork is fast on a horizontal shaft 153 journaled in bearings in the knee and projecting forwardly beyond the front face of the knee, where it receives an operating handle 155. By the construction described, the handle 155 may cause the fork 151 to rock in a vertical plane and rock the T- 90 lever in a horizontal plane, thereby opening or closing the clutch 49 as desired.

To hold the clutch in its open and closed positions, the rounded end of the T-lever may receive a spring-pressed plunger 157 100 (Figs. 11 and 12) adapted to engage opposite sides of a wedge-shaped projection 159 on a pin 161 secured to a wall of the knee.

Next will be described means to automatically rock the fork 151 and T-lever to 105 shift the clutch by either upward or downward movements of the knee. To accomplish this, a sleeve 163 (Figs. 7, 8 and 11) may be journaled on the shaft 153, referred to, and have a segment 165 adapted to engage a shoulder 167 on the fork 151. A sufficient space is provided between the segment and this shoulder to allow manual 110 rocking of the fork to shift the clutch without interference from the sleeve. An arm 169 (Fig. 15) depends from the sleeve 163 and is engaged by the inner end of a plunger 171, the outer end of which engages a lever 173 fast on a shaft 175 mounted on the knee and having a lever 176 with a pin 176^a in 115 line with a pair of dogs 177 (Figs. 7, 11 and 12) adjustably secured by bolts in a T-shaped slot in the standard. The dogs may be secured in different positions of adjustment and determine the upper and lower 120 limits of travel of the knee.

When the knee is moved vertically downward sufficiently, the lever pin 176^a will en-

- gage the lower dog (Fig. 7) and the lever 176, shaft 175 and lever 173 will be rocked thereby, causing the plunger 171 to move inward against the sleeve arm 169. This 5 will rock the sleeve in a contra-clockwise direction (Figs. 7 and 8) and cause the segment 165 to rock the yoke 151 and the T-lever 147, thereby opening the clutch 49 and interrupting the feed to the knee.
- 10 When the sleeve 165 is not rocked as described to open the clutch, it is held in its position shown in Figs. 7 and 8, by a spring-pressed plunger 179 mounted on the knee and adapted to engage an arm 181 projecting upward from the sleeve.

15 When the knee is moved vertically upward, the lever pin 176^a carried thereby will eventually reach the upper dog and open the clutch 49 and interrupt the feed of the 20 knee in a manner similar to that described for the downward movement of the knee.

25 Next will be described means operable from movement of the saddle to automatically open the clutch and arrest the feed thereof. To accomplish this, the saddle may have a dog 183 (Fig. 7) adjustably secured by a bolt in a T-slot therein, and the lever 173, referred to, is of sufficient length to project upward into the path of this dog.

30 As a result, when the saddle has moved to a position predetermined by the location of the dog, the latter will engage the lever 173, depress the plunger 171 and rock the sleeve to open the clutch in the manner 35 previously described.

35 Next will be described means operable on movement of the table for automatically opening the clutch and arresting the feed of the table. To accomplish this, the sleeve 40 163 may have a tooth space 185 (Figs. 7 and 8) therein extending axially thereof adapted to receive a tooth 186 on one end of a lever 187 (Figs. 7, 14, 14^a) on a screw 189 mounted in a boss 191 carried by the 45 saddle bracket 115, referred to. The opposite end of this lever bears against the lower end of a plug 193 mounted in the gear hub 127 journaled in the saddle bracket. The upper end of this plug bears against a crank 50 195 (Fig. 4) on a horizontal shaft 197 journaled in bearings in the saddle. This shaft has a pinion 199 fast thereon meshing with a rack plunger 201 adapted to be engaged by a dog 203 secured by a bolt in different 55 positions of adjustment in a T-slot in a face of the table.

When the table travels horizontally to a position predetermined by the location of the dog, the latter will engage and depress 60 the plunger 201, thereby rotating the pinion 199, its shaft 197 and the crank 195. The latter will depress the plug 193, rock the lever 189 and the sleeve 163. The latter in turn will rock the fork 151 and the T-lever

147, thereby opening the clutch and arrest- 65 ing the feed.

It will be understood that a sufficient number of dogs may be provided for the knee, saddle and table to automatically open the clutch and arrest the feed of said parts 70 in opposite directions.

Having described the mechanism for feeding the knee, saddle and table at different speeds, and the mechanism for manually or automatically arresting any of the feeds, 75 next will be described means operable from the standard for driving the feeding mechanism carried by the knee. To accomplish this, the sleeve shaft 81, referred to, in the knee, may have a gear 205 (Fig. 12) fast 80 thereon adapted to mesh with and be driven by a gear 207 (Fig. 4) beneath the gear 205 and fast on the hub of a bevel gear 209 loosely journaled on a stud 211 secured to the knee. This bevel gear is adapted to be 85 driven in opposite directions by bevel gears 213 having hubs journaled in bearings in a box 215 secured to the face of the knee adjacent the standard. The bevel gears 213 are loosely mounted on a vertical shaft 217 90 journaled in bearings 219 (Fig. 1) in a yoke bracket 221 mounted on the standard, said shaft being confined against vertical movement.

95 A clutch 223 (Figs. 1 and 5) is splined to the shaft 217 and mounted between the bevel gears 213. The clutch and gears have opposed teeth, so that either of said gears may be connected to the vertical shaft to transmit rotation to the bevel gear 209 and 100 thence to the feed mechanism carried by the knee.

To shift the clutch to connect the gears alternatively to said shaft according to the direction of feed desired, the clutch is 105 mounted in a bearing arm 225 (Fig. 5) projecting laterally from an elongated bearing 227 mounted in and adapted to slide in the bearing box 215, referred to, carried by the knee. To shift the bearing 227 vertically, a 110 transverse groove 229 (Figs. 5 and 6) is formed therein receiving a sliding block 231 having a crank pin 233 therein projecting from the head 235 of a sleeve 237 (Fig. 12) splined to an end of a control shaft 239 projecting through and beyond the front face of the knee, where it has an operating handle 241 pivotally connected thereto. When this handle is rocked it will turn the shaft 239, the sleeve 237 and the crank pin 233 shifting 115 the bearing 227 vertically to cause the clutch 223 to connect either of the bevel gears 213 with the shaft 217.

120 To drive the shaft 217, a bevel gear 243 (Fig. 1) may be mounted fast thereon adjacent the upper end thereof and mesh with a bevel gear 245 (Fig. 2) fast on a sleeve shaft 247 journaled in the bearing bracket 221, re-

ferred to. This sleeve shaft is splined to an axially movable shaft 249 having one end mounted in said sleeve shaft and its opposite end projecting into and splined to a sleeve shaft 251 (Fig. 13) journaled in a bearing on the standard.

The shaft 249 may be driven from the spindle 5, referred to. To accomplish this, said spindle is provided with a pinion 253 (Fig. 1) driving an intermediate gear 255 on a stud 257 on the standard, said intermediate gear meshing with a gear 259 loose on the sleeve 251, referred to. A clutch 261 fast on the shaft 249 has teeth adapted to engage 10 teeth projecting from the hub of the gear 259. When the shaft 249 is shifted to the right (Fig. 1), the clutch will connect the gear 259 to said shaft, which will drive the vertical shaft 217, and the latter in turn will 15 transmit the drive to the feed mechanism carried by the knee, the direction of feed being controlled by the shifting of the clutch 223 to connect either of the bevel gears 213 with the vertical shaft.

25 Next will be described simple and effective means for imparting a rapid feed or traverse to the knee, saddle and table, or any of them. To accomplish this, a rotor, in the present instance, in the form of a pulley 263 30 (Figs. 1 and 13) may be loosely mounted on the sleeve 251 and driven from a belt (not shown) at the speed desired. This pulley may be directly connected to the shaft 249 by a friction clutch 265 similar to the one 35 shown in Letters Patent to Wm. F. Groene, No. 959,520, dated May 31, 1910. This clutch may be operated by a conical member 267 fast on the shaft 249, the construction being such that when the shaft is shifted to 40 the left, the clutch will expand and connect the pulley to the shaft, and when the latter is shifted to the right, it will release the friction clutch and disconnect the pulley from the shaft. Thus, sliding of the shaft 249 45 serves the dual function of connecting and disconnecting the gear 259 to the shaft and of connecting and disconnecting the pulley to the shaft. The movement of the shaft to the left opens the gear clutch 261 and closes 50 the pulley clutch 265, and conversely the shifting of the shaft to the right closes the gear clutch and releases the pulley clutch. However, the construction is so arranged that the pulley clutch is never closed until the gear 55 clutch has been opened, therefore, the rapid traverse cannot be thrown into operation until after the slower feed obtained by the gear 259 has been interrupted.

60 Next will be described simple and effective means for shifting the shaft 249 axially for opening and closing the clutches as described. To accomplish this, a collar 269 (Figs. 2 and 3) on the shaft 249 has a circumferential groove therein receiving a fork 271 pivotally 65 mounted on the bracket 221, referred to, and

having a toothed sector 273 meshing with a rack plunger 275 mounted in a socket on said bracket. This plunger is urged to the left (Fig. 2) by a helical spring 277 confined between one end of said socket and an enlargement 279 on said plunger. A roller 281 on one end of said plunger is engaged by a cam 283 fast on a vertical shaft 285 parallel to the transmission shaft 217, referred to, and projecting through a bearing in the box 215 70 on the knee. A toothed sector 287 (Figs. 5 and 12) is splined to the shaft 285 and meshes with a rack bar 289 secured to a block 291 (Fig. 12) confined axially on the control shaft 239, referred to.

75 By the construction described, when the control shaft is shifted axially inward, it will cause the rack 289 to rock the sector 287 and the vertical shaft 285. The latter in turn will rock the cam 283, thereby pushing the rack plunger 275 to the right (Fig. 2). This will rock the fork 271 and shift the shaft 249 to the left (Fig. 1), thereby opening the gear clutch 261 and closing the pulley clutch. This will cause the rapid drive of 80 the feed mechanism carried by the knee.

When the control shaft 239 is shifted axially outward, the clutch shaft 249 will be moved to the right of Fig. 1, thereby first opening the pulley clutch and then closing 95 the gear clutch. This will cause the shafts 249 and 217 to be rotated to impart the working feed to the mechanism carried by the knee.

100 It will be noted that the handle 241 serves the dual function of operating the clutch 223 to control the direction of feed, and of shifting the shaft 249 to control the opening and closing of the gear clutch and pulley clutch.

105 It is important that the rapid traverse rotor or pulley should not be brought into operation while the knee, saddle and table, or any of them, are being fed. To prevent this occurrence, the direction clutch 223 is always disconnected from the bevel gears 213 to interrupt the feed before the pulley clutch can be closed. To accomplish this, the controlling handle 241 may be provided with a guard 293 (Figs. 12 and 16) having an internal flange 295 with a notch 297 therein. A pin 299 on an enlargement on the shaft 239 may escape through said notch to and from chambers 301 and 303 in said guard only when said handle 241 is in a predetermined position of adjustment, such that the clutch 223 is in its intermediate position, disconnecting both of the bevel gears 213 from the shaft 217. After the handle has been rocked to this predetermined position, it may be shifted axially to operate the gear clutch 261 and the pulley clutch 265. After the pin 299 has passed through its groove into either of the chambers 301 and 303, the handle 241 may be rocked to shift the clutch 223 to connect either of the bevel gears 213 110 115 120 125 130

with the shaft 217 according to the direction of feed desired.

The handle 241 may have a ball 241^a formed thereon working in a segmental slot 241^b in the guard to allow the rocking of the handle to impart the axial and rotative adjustments to the controlling shaft 239.

The handle is located at the front of the knee, where it is conveniently accessible to the operator for controlling the direction of feed, the working feed and the rapid traverse. The clutch 223 serves to control the direction of feed during both the working feed and the rapid traverse.

15 Preferably the rapid traverse is obtained independently of the speed change mechanism in the knee. To accomplish this, a gear 305 (Fig. 12) may be mounted loose on the sleeve shaft 81, referred to, and may 20 be connected thereto by a clutch 307 having teeth adapted to engage teeth on a face of said gear. The gear 305 drives a pinion 309 (Fig. 11) above the gear 305 and fast on a stud shaft journaled in bearings in the knee 25 and having a wide-faced gear 311 fast thereon meshing with the shiftable gear 41, referred to, in all of the positions of the latter for feeding the knee, saddle and table. The wide-faced gear 311, pinion 309 and 30 gear 305 will rotate idly during the working feeds, but when the clutch 307 is closed, the gear 305 is connected to the sleeve shaft 81 and becomes effective to drive the shiftable gear 41 independently of the speed 35 change mechanism mounted in the knee.

To operate the clutch 307, a rocking plate 313 (Fig. 12) may be fulcrumed on a stud 315 in the knee and have an arm carrying a shoe 313^a ergaging said clutch, and an 40 arm carrying an adjustable screw 317 adapted to engage a cam projection 319 on the block 291, referred to, carried by the control shaft 239. The plate 313 has a socket 321 containing a spring-pressed plunger 323 45 abutting against a lug 325 projecting inward from the wall of the knee. This plunger tends to rock the plate in a contra-clockwise direction (Fig. 12) and close the rapid traverse clutch 307.

50 When, however, the control shaft 239 is shifted to the left (Fig. 12), the cam projection 319 on the block 291 will rock the plate 313 in a clockwise direction against the resistance of the spring-pressed plunger, 55 thereby holding the clutch 307 open. When the control shaft is shifted to the left, the pulley clutch is opened and a gear clutch is closed. Hence, so long as the control shaft remains in this position, the cam projection 60 319 will prevent closing of the rapid traverse clutch 307.

When, however, the control shaft 239 is shifted to the right (Fig. 12) to close the pulley clutch and release the work feed clutch, the cam projection 319 will be moved

out of engagement with the pin 317, thereby releasing the clutch operating plate 313 to the action of its spring-pressed plunger 323 and causing the rapid traverse clutch 307 to close. Thus, the opening and closing of the rapid traverse clutch is controlled incidentally to the shifting of the control shaft 239 axially to control the work feed and pulley clutches.

When the rapid traverse clutch is closed, 75 the clutch 49 of the work feed mechanism should be open. To accomplish this, a cone sleeve 327 (Fig. 12) may be mounted on the control shaft 239 and engage a pin 329 adjustably mounted on an arm of the T-lever 80 147, referred to. The construction is such that when the control shaft 239 is shifted to the right, the cone sleeve 327 will press the pin 329 outward, thereby rocking the T-lever in a clockwise direction to open the 85 clutch 49.

Thus, this clutch will be opened incidentally to the shifting of the control shaft for closing the rapid traverse clutch 307 and for closing the pulley clutch. With a single 90 movement of the control shaft, the rapid traverse feed may be brought into play, and when this feed is completed, the control shaft may be given a single movement to automatically interrupt the rapid traverse 95 and return again to the work feed previously in operation.

Means has been described for automatically arresting the knee, saddle and table feeds when the work feeds are taking place. 100 It is also important to provide means to arrest the rapid traverse feed and prevent travel of the knee, saddle and table sufficiently to cramp or injure their feed screws. To accomplish this, the control plate for the 105 rapid traverse clutch 307 may have a boss 331 (Figs. 8, 9 and 12) thereon containing a spring-pressed dog 333 adapted to engage a notch 335 in an arm 337 fast on the shaft 153, referred to, for operating the fork 151 110 111 for rocking the T-lever 147 for shifting the work feed clutch 49.

When the control plate for the rapid traverse clutch 307 is held in position to maintain the clutch open, a lug 339 (Fig. 8) on the block 291, referred to, engages the dog 333 and holds the same out of range from the notch 335, but when the rapid traverse clutch is closed, the dog 333 is rocked to the left (Fig. 8) away from said lug, thereby 115 permitting said dog to move into range of said notch. As a consequence, when any of the stop dogs for the knee, saddle and table become effective to rock the shaft 153, the arm 337 will act through the dog 333 120 and rock the plate 313 in a direction to open the rapid traverse clutch 307, thereby arresting the feed of the knee, saddle and table according to which of them is being fed. The rocking of the plate to open the clutch 130

moves the dog 333 back to its position beneath the lug 339 on the block 291, and depresses said dog out of range from the notch 335, where it will not interfere with the 5 rocking of the shaft 153 in controlling the work feed clutch 49.

- The stop dogs referred to may be adjusted on the standard, saddle and knee in suitable positions for preventing overfeeds 10 of the knee, saddle and table, and these dogs may serve to rock the T-lever 149 to open the work feed clutch 49 and prevent over travel of the work feeds as well as over travel of the rapid traverse feeds.
- 15 By the machine described, simple and compact means is provided in the knee for feeding the knee, saddle and table, or any of them, at different speeds for working feeds; simple and effective means for automatically arresting said working feeds; simple and effective means for changing from the working feed to the rapid traverse, and vice versa; and simple and effective means for controlling the direction 25 of feed during the working feed and the rapid traverse. All of the controlling levers for the aforesaid operations are mounted on the knee, where they are conveniently and readily accessible to the operator.
- 30 The term "rotor" is used in the specification and claims to mean a pulley, gear, wheel, or other suitable rotatable driving element.

It will be understood that the invention 35 is not limited to the specific embodiment shown, but that various deviations may be made therefrom, without departing from the spirit and scope of the appended claims.

Claims:

- 40 1. A machine of the character described comprising in combination, a standard, a work support movably mounted thereon, feed and rapid traverse rotors mounted on said standard, transmission means between 45 said rotors and said support, clutch means on said standard for alternatively rendering said rotors effective, and controlling means for said clutch means provided with operating means on said support.
- 50 2. A machine of the character described comprising in combination, a standard, a work support movably mounted thereon, feed and rapid traverse rotors mounted on said standard, transmission means for im- 55 parting movement from said rotors to said support, a clutch for controlling the direction of feed of said support by both rotors, and controlling means for said clutch pro- 60 vided with operating means on said sup- port.
- 60 3. A machine of the character described comprising in combination, a standard, a work support movably mounted thereon, feed and rapid traverse rotors, transmission 65 means for imparting movement from said

rotors to said support, clutch means for alternatively rendering said rotors effective to feed said support, a clutch for controlling the direction of feed of said support by both of said rotors, and controlling means for both said clutch means and clutch provided with operating means on said support. 70

4. A machine of the character described comprising in combination, a standard, a work support movably mounted thereon, feed and rapid traverse rotors mounted on said standard, transmission means for imparting movement from said rotors to said support, and control means on said standard for alternatively rendering said rotors effective to feed said support, a controlling handle on and operable from said support, and connections between said handle and control means. 80

5. A machine of the character described comprising in combination, a standard, a work support movably mounted thereon, feed and rapid traverse rotors mounted on said standard, transmission means for imparting movement from said rotors to said support, and controlling means extending from said standard to said support, and operable from the latter to control said rotors when said support is at various elevations. 85

6. A machine of the character described comprising in combination, a standard, a work support movably mounted thereon, feed and rapid traverse rotors mounted on said standard, transmission means for imparting movement from said rotors to said support, and a single control on said support for determining the direction of feed of said support by either of said rotors. 95

7. A machine of the character described comprising in combination, a standard, a work support movably mounted thereon, feed and rapid traverse rotors mounted on said standard, transmission means common to said rotors for imparting movement from said rotors to said support, and controlling means on said support for rendering either of said rotors effective to feed said support. 105

8. A machine of the character described, comprising in combination, a standard, a work support movably mounted thereon, feed and rapid traverse rotors mounted on said standard, transmission means for imparting movement from said rotors to said work support, and a single control on said support for rendering either of said rotors effective and for determining the direction of feed of said support. 115

9. A machine of the character described comprising in combination, a standard, a work support movably mounted thereon, rotors mounted on said standard for feeding said support at different speeds, means to transmit movement from said rotors to said support, clutches for rendering either of 120

130

- 5 said rotors effective and determining the direction of feed, and a single control for said clutches mounted on said support.
10. A machine of the character described, comprising in combination, a standard, a knee mounted on said standard, a work support movably mounted on said knee, a work feed rotor and a rapid traverse rotor mounted on said standard, means to transmit movement from said work feed rotor to said support at variable speeds, and a single control mounted on said support for rendering said rotors alternatively effective and for determining the direction of movement of said support when fed by either of said rotors.
11. A machine of the character described comprising in combination, a standard, a work support movably mounted thereon, feed and rapid traverse rotors mounted on said standard, and transmission means between said rotors and said support including an upright shaft mounted on said standard, gear means carried by said support movable along said upright shaft, and a control for rendering said rotors alternatively effective mounted on said work support.
12. A machine of the character described comprising in combination, a standard, a work support movably mounted thereon, driving means on said standard, transmission means between said driving means and said support including a vertical shaft mounted on said standard and held against axial movement, gear means carried by said support movable axially of said shaft, and a control for rendering said driving means effective or ineffective at will mounted on said support.
13. A machine of the character described comprising in combination, a standard, a work support movably mounted thereon, driving means mounted on said standard, and transmission means between said driving means and said support including an upright shaft mounted between opposed faces of said standard and support.
14. A machine of the character described comprising in combination, a standard, a work support movably mounted thereon, driving means mounted on said standard, transmission means between said driving means and said support including an upright shaft, and a pair of gears mounted on said shaft, and a control for said driving means and for alternatively connecting said gears to said shaft, said control being mounted on said work support.
15. A machine of the character described comprising in combination, a standard, a work support movably mounted thereon, driving means on said standard, transmission means between said driving means and said support including an upright shaft mounted on said standard, a pair of gears on said shaft, an intermediate gear meshing with said gears, and means on said support carrying said gears.
16. A machine of the character described comprising in combination, a standard, a work support movably mounted thereon, driving means on said standard, transmission means between said driving means and work support including an upright shaft, gears loose on said shaft, a clutch for alternatively connecting said gears to said shaft, and a control on said support for said driving means and for operating said clutch.
17. A machine of the character described comprising in combination, a standard, a work support movably mounted thereon, driving means on said standard, feeding means on said support, transmission means between said driving and feeding means including an upright shaft on said standard, gears on said shaft, a clutch for alternatively connecting said gears to said shaft to control the direction of said feeding means, and means for shifting said clutch.
18. A machine of the character described comprising in combination, a standard, a work support movably mounted thereon, driving means on said standard, feeding means on said support, transmission means between said driving means and feeding means including an upright shaft on said standard, gears on said shaft carried by said support, a clutch for alternatively connecting said gears to said shaft, and means on said support for shifting said clutch.
19. A machine of the character described comprising in combination, a standard, a work support movably mounted thereon, driving means on said standard, feeding means on said support, transmission means between said driving means and feeding means including an upright shaft, gears on said shaft, a clutch for alternatively connecting said gears to said shaft, a member carrying said clutch, and means for shifting said member including a shaft extending through the knee and having an operating handle thereon.
20. A machine of the character described comprising in combination, a standard, a work support movably mounted thereon, driving means on said standard, transmission means between said driving means and support including an upright shaft, a pair of gears on said shaft, a clutch for connecting said gears to said shaft, a carrier for said clutch having a groove therein, a block sliding in said groove, a shaft on said support having a crank pin projecting into said block, and an operating handle for said shaft.
21. A machine of the character described comprising in combination, a standard, a work support mounted thereon, driving means on said standard, transmission means

between said driving means and support including an upright shaft, a pair of gears loose on said shaft, a sliding clutch for connecting either of said gears to said shaft, and means carried by said support for shifting said clutch in any of the positions of adjustment of said support.

22. A machine of the character described comprising in combination, a standard, a work support mounted thereon, work feed and rapid traverse rotors on said standard, transmission means for imparting movement from said rotors to said support including an upright shaft on said standard, a pair of gears on said shaft, a clutch for connecting either of said gears to said shaft, clutch means on said standard for rendering either of said rotors effective, and controlling means for said clutches including a shaft having an axial movement to shift said rotor clutches and a rotative movement to shift said gear clutch.

23. A machine of the character described comprising in combination, a standard, a work support movably mounted thereon, work feed and rapid traverse rotors on said standard, transmission means between said rotors and said support including an upright shaft, gears thereon, a clutch for connecting either of said gears to said shaft, clutches for rendering either of said rotors effective, and controlling means for said clutches including a shaft having axial and rotative movements, one for shifting said rotor clutches and the other for shifting said gear clutch.

24. A machine of the character described comprising in combination, a standard, a work support movably mounted thereon, work feed and rapid traverse rotors, a shaft therefor, an upright shaft driven thereby, gear means on said upright shaft carried by said support, clutches for said rotors, and means to shift said first named shaft axially to operate said clutches.

25. A machine of the character described comprising in combination, a standard, a work support movably mounted thereon, work feed and rapid traverse rotors on said standard, a shaft for said rotors, an upright shaft driven by said shaft, gear means on said upright shaft carried by said support, clutches for connecting either of said rotors to said first named shaft, and means operable from said support for sliding said first named shaft axially to shift said clutches.

26. A machine of the character described comprising in combination, a standard, a work support movably mounted thereon, a pair of rotors on said standard, a shaft for said rotors, clutches for connecting said rotors to said shaft, means to transmit movement from said shaft to said support, and means to slide said shaft in one direction to

open one of said clutches and close the other.

27. A machine of the character described comprising in combination, a standard, a work support movably mounted thereon, and means to feed said support relative to said standard including a pair of rotors mounted on said standard, a shaft for said rotors, a positive clutch for connecting one of said rotors to said shaft, a friction clutch for connecting the other rotor to said shaft, and means to slide said shaft axially to operate said clutches.

28. A machine of the character described comprising in combination, a standard, a work support movably mounted thereon, a pair of rotors on said standard, a shaft for said rotors, transmission means between said shaft and said support, clutches for connecting said rotors to said shaft, and means operable from said support for shifting said shaft axially to operate said clutches.

29. A machine of the character described comprising in combination, a standard, a work support movably mounted thereon, a pair of rotors on said standard, a shaft for said rotors, clutches for connecting said rotors to said shaft, and cam means operable from said support for shifting said shaft axially to operate said clutches.

30. A machine of the character described comprising in combination, a standard, a work support movably mounted thereon, rotors on said standard, a shaft for said rotors, clutches for connecting said rotors to said shaft, and means including a spring-pressed plunger for shifting said shaft to operate said clutches.

31. A machine of the character described comprising in combination, a standard, a work support movably mounted thereon, rotors on said standard, a shaft for said rotors, clutches for connecting said rotors to said shaft, spring means tending to shift said shaft in one direction to operate said clutches, and cam means controlled from said support for shifting said shaft in the opposite direction to operate said clutches.

32. A machine of the character described comprising in combination, a standard, a work support movably mounted thereon, rotors on said standard, a shaft for said rotors, clutches for connecting said rotors to said shaft, means for shifting said shaft axially including an upright shaft, a gear element, a rack meshing with said gear element, and an axially movable control shaft on said support connected to said rack.

33. A machine of the character described comprising in combination, a standard, a work support movably mounted thereon, rotors on said standard, a shaft for said rotors, clutches for connecting said rotors with said shaft, controlling means for said

- clutches including an upright shaft, a gear element carried by said support and splined to said upright shaft, and controlling means on said knee for rotating said gear element.
34. A machine of the character described comprising in combination, a standard, a work support movably mounted thereon, rotors on said standard, a shaft for said 10 rotors, clutches for connecting said rotors with said shaft, means to shift said shaft axially to operate said clutches including a fork, a toothed sector thereon, a rack plunger meshing with said sector, a spring urging 15 said plunger in one direction, a cam for moving said plunger in the opposite direction, an upright shaft secured to said cam, a gear element splined to said upright shaft and movable vertically with said support, 20 a rack on said support meshing with said gear element, an axially adjustable control shaft for shifting said rack, and a handle for operating said control shaft.
35. A machine of the character described 25 comprising in combination, a standard, a work support movably mounted thereon, work feed and rapid traverse rotors mounted on said standard, transmission means between said rotors and said support including an upright shaft, gears thereon, a clutch to connect either of said gears to said shaft, clutches to render either of said rotors effective, controlling means for all of said 30 clutches including a shaft having an axial movement to shift said rotor clutches and a rotative movement to shift said gear clutch, a handle for imparting said movements to said shaft, and means to prevent axial movement of said shaft, excepting 35 when turned to a position to disconnect the gear clutch from said gears.
36. A machine of the character described 40 comprising in combination, a standard, a work support movably mounted thereon, work feed and rapid traverse rotors on said 45 standard, transmission means between said rotors and said support including an upright shaft, gears on said shaft, a clutch to connect either of said gears to said shaft, clutches to render either of said rotors effective, and controlling means for all of said 50 clutches having means to prevent shifting of said rotor clutches excepting when said gear clutch is disconnected from said gears.
37. A machine of the character described 55 comprising in combination, a standard, a work support movably mounted thereon, work feed and rapid traverse rotors on said standard, transmission means between said 60 rotors and said support including an upright shaft, gears on said shaft, a clutch to connect either of said gears to said shaft, clutches to render either of said rotors effective, and controlling means for all of said 65 clutches including a shaft having an axial movement to shift said rotor clutches and a rotative movement to shift said gear clutch, a handle for giving said shaft said movements, and a guard for said handle having means to prevent shifting of said rotor 70 clutches excepting when in a position to disconnect said gear clutch from said gears.
38. A machine of the character described comprising in combination, a standard, a work support movably mounted thereon, 75 and means to feed said support relatively to said standard including different size gears on said support, tumbler gears on said support, means to rock said tumbler gears relatively to said different size gears, and 80 means to shift the latter axially to bring the latter selectively opposite each of said tumbler gears.
39. A machine of the character described comprising in combination, a standard, a work support movably mounted thereon, and means to feed said support relatively to said standard including different size gears on said support, tumbler gears on said support, means to rock said tumbler gears 90 relatively to said different size gears, means to shift the latter axially to bring the latter selectively opposite each of said tumbler gears, and gear means to multiply the speeds obtained by said tumbler gears. 95
40. A machine of the character described comprising in combination, a standard, a work support movably mounted thereon, and means to feed said support relatively to said standard including different size 100 gears on said support, a carrier for said different size gears, tumbler gears on said support, means to rock said tumbler gears relatively to said different size gears, a rack for said carrier, a worm meshing with said 105 rack, a shaft for said worm, and a handle for rotating said worm to shift said rack and carrier to bring the gears thereon selectively opposite any of said tumbler gears.
41. A machine of the character described 110 comprising in combination, a standard, a work support movably mounted thereon, and means to feed said support relatively to said standard including different size gears on said support, tumbler gears on said 115 support, and manually operable means on said support for shifting said different size gears axially and rocking said tumbler gears relatively to said tumbler gears.
42. A machine of the character described 120 comprising in combination, a standard, a work support movably mounted thereon, and means to feed said support relatively to said standard including axially movable different size gears on said support, tumbler 125 gears on said support movable to and from said different size gears, and means including manually operable devices at the front of said support for moving said different size gears axially and for rocking said tum- 130

bler gears relatively to said different size gears.

43. A machine of the character described comprising in combination, a standard, a work support movably mounted thereon, and means for feeding said support relatively to said standard including different size gears on said support, tumbler gears on said support, a shaft, a gear thereon driven by said tumbler gears, a second gear on said shaft, a driven shaft, gears on the latter adapted to mesh with the gears on said first named shaft, and means to render either of the gears on said driven shaft effective to transmit rotation thereto.

44. A machine of the character described comprising in combination, a standard, a work support movably mounted thereon, and feeding means on said support including different size gears, tumbler gears, a shaft, a gear thereon driven by said tumbler gears, a second gear on said shaft, a driven shaft, gears thereon adapted to mesh with the gears on said first named shaft, and means including a clutch to render either of the gears on said driven shaft effective to transmit rotation thereto.

45. A machine of the character described comprising in combination, a standard, a work support movably mounted thereon, and feeding means on said support including different size gears, tumbler gears, a driven shaft, gears thereon, an intermediate shaft, gears thereon adapted to mesh with the gears on said driven shaft, and means to slide one of said gears on said driven shaft to and from meshing engagement with one of the gears on said intermediate shaft.

46. A machine of the character described comprising in combination, a standard, a work support movably mounted thereon, and feeding means on said support comprising different size gears, tumbler gears driven thereby, a driven shaft, gears thereon, an intermediate shaft, gears thereon adapted to mesh with said gears on said driven shaft, and manually operable means on said support for axially shifting said different size gears, rocking said tumbler gears relatively to said different size gears, and for rendering either of the gears on said driven shaft effective to transmit rotation to said driven shaft.

47. A machine of the character described comprising in combination, a standard, a work support movably mounted thereon, and feeding means on said support comprising a sleeve shaft, a gear for rotating said shaft, a shaft telescoping and splined to said sleeve shaft, different size gears on said telescoping shaft, tumbler gears adapted to mesh with said different size gears, manually operable means for shifting said different size gears

and their shaft axially, and manually operable means for rocking said tumbler gears relatively to said different size gears.

48. A machine of the character described comprising in combination, a standard, a knee movably mounted thereon, a saddle on said knee, a table on said saddle, and feeding means for said knee, saddle and table including a driving gear for said knee, a driving gear for said saddle, a driving gear for said table, and a shiftable gear adapted to mesh with any of said driving gears to transmit rotation thereto.

49. A machine of the character described comprising in combination, a standard, a knee movably mounted thereon, a saddle on said knee, a table on said saddle, feed screws for said knee, saddle and table, driving gears for said screws respectively, and a shiftable gear adapted to mesh with any of said gears to transmit rotation thereto.

50. A machine of the character described comprising in combination, a standard, a knee, saddle and table mounted thereon, feed screws for said parts, driving gears for said screws, a shiftable gear adapted to mesh with any of said driving gears to transmit rotation thereto, and manually operable means for controlling said shiftable gear.

51. A machine of the character described comprising in combination, a standard, a knee, saddle and table movably mounted thereon, feed screws for said parts, driving gears for said feed screws, a shiftable gear adapted to mesh with any of said gears to transmit rotation thereto, an axially movable shaft in said knee, means to connect said shaft with said shiftable gear, and a handle for adjusting said axially movable shaft.

52. A machine of the character described comprising in combination, a standard, a knee, saddle and table movably mounted thereon, feed screws for said parts, driving gears for said screws, a shiftable gear adapted to mesh with any of said gears to transmit rotation thereto, and means mounted in said knee for driving said shiftable gear at different speeds.

53. A machine of the character described comprising in combination, a standard, a knee, saddle and table movably mounted thereon, feed screws for said saddle and table, driving gears for said feed screws, a shiftable gear adapted to mesh with either of said driving gears to transmit rotation thereto, and manually operable means for shifting said shiftable gear.

54. A machine of the character described comprising in combination, a standard, a knee, saddle and table movably mounted thereon, feed screws for said parts, driving gears for said screws, a shiftable gear adapted to mesh with any of said driving gears,

driving means for said shiftable gear, and a clutch for disconnecting said shiftable gear from said driving means.

55. A machine of the character described comprising in combination, a standard, a knee, saddle and table movably mounted thereon, feed screws for said parts, driving gears for said screws, a shiftable gear adapted to mesh with any of said gears, driving means for said shiftable gear, a clutch between said driving means and shiftable gear, and manually operable means for controlling said clutch.

56. A machine of the character described comprising in combination, a standard, a knee, saddle and table movably mounted thereon, feed screws for said parts, driving gears for said screws, a shiftable gear adapted to mesh with any of said gears, driving means for said shiftable gear, a clutch between said driving means and shiftable gear, and automatic means to control said clutch operable by movements of said parts.

57. A machine of the character described comprising in combination, a standard, a work support movably mounted thereon, and feeding means for said support mounted thereon and including a clutch, a T-lever for operating said clutch, a fork engaging said T-lever, a shaft carrying said fork, and a handle for turning said shaft.

58. A machine of the character described comprising in combination, a standard, a work support movably mounted thereon, and feeding means for said support mounted thereon and including a clutch, a T-lever for operating said clutch, a fork engaging said T-lever, a shaft carrying said fork, and means to hold said T-lever in position to maintain said clutch open or closed.

59. A machine of the character described comprising in combination, a standard, a work support movably mounted thereon, and feeding means for said support including a clutch, a T-lever mounted in said knee for shifting said clutch, a spring-pressed plunger on said lever, and a member coöperating with said plunger to hold said clutch in open and closed position.

60. A machine of the character described comprising in combination, a standard, a knee and a saddle movably mounted thereon, feed screws for said knee and saddle, and driving means for said screws including a clutch, a lever connected to said clutch, a rocking member for shifting said lever, a shaft carrying said rocking member, a sleeve on said shaft, a plunger projecting from said sleeve outward from said knee, a lever pivotally mounted on said knee engaging said plunger, and dogs on said standard and saddle to operate said lever to shift said plunger, sleeve, member and clutch lever to open said clutch.

61. A machine of the character described

comprising in combination, a standard, a knee, saddle and table movably mounted thereon, feed screws for said parts, and driving means for said feed screws including a clutch, a lever connected to said clutch, a rocking member connected to said lever, a shaft carrying said rocking member, a sleeve for said shaft having a lug projecting therefrom, a plunger extending from said lug outward through said knee, a lever engaging said plunger, dogs on said standard and saddle for operating said last named lever, dogs on said table, and means to transmit movement from said table dogs to said sleeve.

62. A machine of the character described comprising, in combination, a standard, a knee, saddle and table movably mounted thereon, feed screws for said parts, a bracket depending from said saddle to its feed screw, driving means for said feed screws including a clutch, a dog on said table, and means extending from said table through said bracket to said clutch for opening the latter to arrest the feed of said table.

63. A machine of the character described comprising in combination, a knee, a saddle and table movably mounted thereon, feed screws for said saddle and table, a bracket connecting said saddle with its feed screw, driving means for said feed screws including a clutch, a dog on said table, and means to transmit movement from said dog to said clutch including a plug in said bracket.

64. A machine of the character described comprising in combination, a knee, a saddle swiveled thereon, a table movably mounted on said saddle, a feed screw for said table, driving means for said feed screw including a clutch in the knee, and means operable from said table to open said clutch having transmitting means extending axially through the swivel axis of the saddle.

65. A machine of the character described comprising in combination, a knee, a saddle swiveled thereon, a table on said saddle, a feed screw for said table, driving means for said screw including a clutch in the knee, and means operable from said table to open said clutch including a rack plunger in said saddle, a pinion meshing therewith, a shaft for said pinion, a crank on said shaft, a plunger actuated by said crank and extending through the swivel axis of said saddle, a lever carried by said saddle actuated by said last-named plunger, a sleeve mounted in said knee having a long tooth slot engaged by said lever, a shaft in said sleeve, a fork on said shaft, and a lever in said knee extending from said fork to said clutch.

66. A machine of the character described comprising, in combination a knee, a work support thereon, a feed screw for said work support, driving means for said feed screw including a clutch in said knee, and means for operating said clutch including a lever,

- a fork engaging said lever, a shaft for said fork, a sleeve on said shaft for rocking said fork, and means automatically to rock said sleeve.
- 5 67. A machine of the character described comprising, in combination, a knee, a work support thereon, a feed screw for said work support, driving means for said feed screw including a clutch in said knee, and means 10 to operate said clutch including spring means tending to close said clutch, and automatic means for opening said clutch. 70
- 15 68. A machine of the character described comprising, in combination, a knee, a work support thereon, a feed screw for said work support, driving means for said feed screw including a clutch in said knee, and means 20 to operate said clutch including a shaft, a fork thereon, a sleeve on said shaft, means 75 to shift said sleeve in one direction to open said clutch, and spring means tending to close said clutch. 80
- 25 69. A machine of the character described comprising, in combination, a knee, a work support thereon, a feed screw for said work support, driving means for said feed screw including a clutch in said knee, and means 30 to operate said clutch including a lever connected to said clutch, a fork connected to 85 said lever, a shaft for said fork, a handle on said shaft to manually control said clutch, and means automatically to rock said fork from movement of said work support. 90
- 35 70. A machine of the character described, comprising, in combination, a standard, a knee thereon, a work support on said knee, a work feed rotor, a rapid traverse rotor, transmission means extending from said rotors to said work support to feed the latter, including a clutch in the knee for controlling the rapid traverse, and means for automatically opening said clutch to arrest the rapid traverse operable from movement of said work support. 95
- 40 71. A machine of the character described, comprising, in combination, a standard, a knee thereon, a work support on said knee, a work feed rotor, a rapid traverse rotor, transmission means extending from said rotors to said work support to feed the latter, including a clutch in said knee for controlling the work feed, a clutch in the knee for controlling the rapid traverse, and means for alternatively rendering said rotors effective including means for automatically 100 opening the rapid traverse clutch and closing the work feed clutch in the knee when the work feed rotor is rendered effective to feed the work support. 105
- 45 72. A machine of the character described, comprising, in combination, a standard, a knee thereon, a work support on said knee, a work feed rotor, a rapid traverse rotor, transmission means extending from said rotors to said work support to feed the latter, including a clutch in said knee for controlling the work feed, a clutch in the knee for controlling the rapid traverse, and means for alternatively rendering said rotors effective including means for automatically closing the rapid traverse clutch in the knee and opening the work feed clutch when the rapid traverse rotor is rendered effective to feed the work support. 110
- 50 73. A machine of the character described, comprising, in combination, a standard, a knee thereon, a work support on said knee, a work feed rotor, a rapid traverse rotor, transmission means extending from said rotors to said work support to feed the latter, including a clutch in the knee for controlling the rapid traverse, and means for shifting said clutch. 115
- 55 74. A machine of the character described, comprising, in combination, a standard, a knee thereon, a work support on said knee, a work feed rotor, a rapid traverse rotor, transmission means extending from said rotors to said work support to feed the latter, including a clutch in the knee for controlling the rapid traverse, and means for automatically opening said clutch to arrest the rapid traverse operable from movement of said work support. 120
- 60 75. A machine of the character described, comprising, in combination, a standard, a knee thereon, a work support on said knee, a rapid traverse rotor, transmission means extending from said rotor to said work support to feed the latter, including a clutch in the knee, controlling means for said rotor having means for automatically closing said clutch when said rotor is rendered effective to feed the work support, and means for automatically opening said clutch to arrest the rapid traverse feed. 125
- 65 76. A machine of the character described, comprising, in combination, a standard, a work support movably mounted thereon, a work feed rotor and a rapid traverse rotor mounted on said standard, means to transmit movement from said rotors to said work support including clutch means for alternatively rendering said rotors operative to move the support, clutch means for determining the direction of movement of said support, and a single control operable from said support for shifting both of said clutch means. 130
72. A machine of the character described, comprising, in combination, a standard, work supporting means movably mounted thereon, rotors mounted on said standard for feeding said supporting means at different speeds, means to transmit movement from said rotors to said supporting means including variable speed mechanism mounted on said supporting means, and a single control

mounted on said supporting means for rendering either of said rotors effective and for determining the direction of feed of said supporting means.

- 5 78. A machine of the character described, comprising in combination, a standard, a knee, saddle and table movably mounted thereon, feed screws for said parts, a variable speed transmission mechanism carried

by the knee to selectively drive any one of 10 said feed screws, and means carried by said knee to render said variable speed transmission mechanism effective at will to rotate any of said feed screws.

In testimony whereof, I have signed my 15 name to this specification.

WILLIAM L. SCHELLENBACH.
